UNITED STATES PATENT OFFICE

2,048,747

BOILER

Aaron Klotzman, Baltimore, Md., assignor to May
Oil Burner Corporation, a corporation of Maryland

Application July 30, 1934, Serial No. 737,657

15 Claims. (Cl. 122—225)

This invention relates to boilers for heating purposes and has particular application to the type of boilers wherein the gaseous products of combustion or other heating gases are directed through a gas passageway or conduit surrounded by water compartments of various constructions and which are employed with low pressure steam or hot water house-heating systems.

Among the objects of this invention is to provide a boiler of this kind having a main water chamber and an auxiliary quick-heating water chamber separate from each other but connected by outside conduit means for fluid circulation.

A further object of this invention consists in the use of a water-lined auxiliary quick-heating chamber as the floor and vertical walls of the fire pot of the boiler in combination with the outside, fluid-circulation, conduit means.

More specifically, it is an object of this invention to provide a boiler as above described and comprising a plurality of section castings with passageways and partition means in proper registry to form the main water compartment, the auxiliary water compartment and fire pot and heating gas compartment, and to provide these section castings with outside integrally-cast conduits connecting the main water compartment with the auxiliary water compartment.

Other, further, and more specific objects of this invention will become readily apparent to persons skilled in the art from a consideration of the following description when taken in conjunction with the accompanying drawings wherein:

Fig. 1 is a side elevation of a boiler embodying my invention showing the use of two intermediate section castings with front and rear section castings.

Fig. 2 is a vertical section along line 2—2 of Fig. 1 and between the front casting and the adjacent intermediate casting, portions of the apparatus being broken away to show the interior construction of a casting and the disposition of the outside conduits connecting the main and auxiliary water compartments.

Fig. 3 is a vertical longitudinal section of the boiler shown in Fig. 1 and taken on line 3—3 of Fig. 2.

Fig. 4 is a side elevation of a modified form of my invention, a portion of the device being broken away to illustrate the interior construction of the section castings which form part of the main water compartment but which are not part of the auxiliary water compartment.

Fig. 5 is a section along line 5—5 of Fig. 1 and of Fig. 4.

Fig. 6 is a section along line 6—6 of Fig. 4.

The boiler shown in Figs. 1 to 3 comprises the front section casting 1, the intermediate section castings 2 and the rear section casting 3. The front casting 1 contains the opening 4 through which passes the pipe 5, commonly known as the "wind pipe", extending from an oil burner B, preferably of the pressure atomizing type. This front casting 1 is also provided with passageways 6, a cavity 7 and the hollow portions 8 and 9. The intermediate castings 2 are provided with passageways 10, 11 and 12 and hollow portions 13 and 14. The rear casting 3 is formed with the passageways 15 and 16, the cavity 17, and hollow portions 18 and 19.

When the castings 1, 2 and 3 are assembled in operative position, the passageways 6 in casting 1 are in registry and continuous with corresponding passageways 10 in the adjacent intermediate casting 2. These passageways 10 are in registry and continuous with corresponding passageways 10 in the other intermediate casting 2, and these latter passageways 10 are in registry and continuous with corresponding passageways 15 in casting 3. The corresponding passageways 11 in the intermediate castings 2 are in registry and continuous with each other, and the passageways 16 in casting 3 are in registry and continuous with corresponding passageways 11 in the adjacent intermediate casting. The large passageway 12 in each of the intermediate castings 2 is in registry and continuous with that in the other casting 2, one of these large passageways 12 also being in registry and continuous with the cavity 17 in the rear casting 3, while the other large passageway 12 is continuous and in partial registry with the cavity 7 in the front casting 1.

Secured to the rear casting 3 is a door or cover disposed over the passageways 15 and 16 and of sufficient depth to afford a connecting-passage 21 between these passageways 15 and 16.

The large passageway 12 in each of the intermediate castings 2 and the cavities 7 and 17 in the front casting 1 and rear casting 3, respectively, provide both a fire pot 22 which receives the combustible mixture from the oil burner B through the pipe 5 and wherein the combustible mixture is burned, and a heating gas compartment in open and direct communication with the fire pot, which heating gas compartment includes the upper part 50 of cavity 7 in casting 1, passageways 11 and 16, connecting-passage 21 and passageways 15, 10 and 6. The heating gases exit through pipe 23, which connects with a smoke stack (not shown).

The floor and the vertical walls of the fire pot 55

are preferably lined with a coating 24 of plastic refractory material of adequate thickness to absorb heat and to radiate heat back to the flame of the burner and sufficiently thin to promptly transfer heat therethrough to the fluid in the hollow portions 9.

The materials employed for making a suitable plastic refractory for use in my boiler may be selected from a wide range of substances commonly employed in the boiler art and which include silicon carbide, raw fire clay, calcined fire clay, magnesium oxide, chrome ores, mica, talc, quartz, kaolin, diatomaceous and infusorial earths, tripoli, kieselguhr, alundum, fire brick, magnesite, ganister, Portland and hydraulic cements, gypsum, anhydrite, volcanic scoriae, and slag. Some of these materials may be used alone, while all of these substances have been employed in combinations of two or more in various compositions, the proportions being varied to meet the particular needs and fancy of the manufacturer and/or user. These materials are comminuted to the desired size and a suitable binder in liquid form is added to yield a plastic mixture suitable for molding and/or application in plastic form as may be desired.

In the specification and claims the term plastic refractory material has reference to a substance prepared from materials, such as are described above, and which is plastic during its application and subsequently becomes rigid.

The hollow portion 8 in the front casting 1, the hollow portion 13 in each of the intermediate castings 2 and the hollow portion 18 in the rear casting 3 form the main water compartment of the boiler. These hollow portions are separate from each other and are in communication only through the slip nipples 25 which connect adjacent castings at the top of the main water compartment.

The hollow portion 9 in the front casting 1, the hollow portion 14 in each of the intermediate castings 2 and the hollow portion 19 in the rear casting 3 form the auxiliary quick-heating water compartment of the boiler as well as the water lining for the fire pot 22. In my preferred constructions, these hollow portions are separate from each other but are in communication with each other by the slip nipples 25.

In each casting there is provided an integral partition 26 which separates the hollow portion of the main water compartment from the hollow portion of the auxiliary water compartment. These partitions 26 are preferably obliquely inclined to the vertical walls of the boiler and, when thus inclined, possess the advantages of better direction of the flow of water into the outside conduits, avoiding the formation of air pockets and also of avoiding the setting up of objectionable eddies in the hot water. If desired, however, these partitions may be perpendicular to the vertical walls of the boiler. The refractory lining 24 generally extends to or slightly beyond these partitions.

Communication between the main water compartment and the auxiliary water compartment is established by external conduits or pipes which are cast integral with but outside of the rest of the casting of which the conduit forms a part. In my preferred form, I provide each casting with an outside integral conduit 27 which extends from the upper part of the hollow portion of water passageway in the casting forming part of the auxiliary water compartment to the upper part of the hollow portion or water passageway in the casting forming part of the main water compartment.

These conduits conduct heated water or steam from the upper part of the auxiliary quick-heating water compartment to the upper part of the main water compartment. My preferred construction also provides each casting with an outside integral conduit 28 which extends from the lower part of the hollow portion or water passageway in the casting forming part of the main water compartment to the lower part of the hollow portion or water passageway in the casting forming part of the auxiliary water compartment. These conduits serve to bring the cooler water from the main water compartment above to the auxiliary quick-heating water compartment below.

I have found that the best results are derived by having the conduits 27 extend from the upper part of the auxiliary water compartment to the upper part of the main water compartment, and the conduits 28 extend from the lower part of the main water compartment to the lower part of the auxiliary water compartment, but satisfactory results may under various conditions be obtained where the conduit openings are located in other positions with respect to the water compartments.

Instead of providing each of the castings with one or more of the upcomer conduits 27 and one or more of the downcomer conduits 28, either upcomer or downcomer conduits may be left off some of the castings or, if desired, assemblies may be made including one or more castings having none of these conduits. Where a conduit serves the hollow portions or water passageways of more than one casting, provision is made for sufficient intercasting fluid passage.

If it is desired to supply water to the auxiliary water compartment, in addition to that which comes from the main water compartment through the conduits 28, such other supply may be provided through the pipe 29.

The hot water from the main water compartment exits through the outlets 30 and 31 to the heating system of the house or for such other purposes as may be desired, and make up or return water enters the boiler through the pipe 29.

The section castings are bolted together and held in gas and water tight relation by bolts 32 or other suitable means. Flanges 33 may be provided so as to afford a closer and tighter fit at the junction between adjacent section castings.

In the modification shown in Fig. 4, the intermediate section castings 2 and the rear section casting 3 are like the corresponding section castings illustrated in Figs. 1 to 3. However, the upper portion of the section casting 34 of Fig. 4 which corresponds to the section casting 1 in Figs. 1 and 2 is so constructed that a section casting 35, such as shown in Fig. 6, may be positioned adjacent thereto and thus provide an extension of the heating gas compartment and an enlargement of the main water compartment. In Fig. 4, there are shown three of these shorter intermediate castings 35, each of which contain gas passageways 36 and water passageways 37. This boiler also comprises the end section casting 38 which has the water passageways 39 and the gas passages 40. The gas passages 36 in each of the castings 35 are in registry and continuous with the gas passages 6 in section 34 and the gas passages 40 in section 38. These sections are also connected at the top and bottom by slip nipples 25. The water passageways 37 and 39 form part of the main water compartment of the boiler. A pipe 41 leads to the smoke stack.

This form of boiler provides for an increase in capacity of the main water compartment without increasing the capacity of the auxiliary quick-heating water compartment. Also, the space 5 below the main water compartment may be conveniently employed for the oil burner B, as shown in Fig. 4.

The sections of the boilers constituting my present invention may be economically, conveniently and cheaply cast, are easy to transport and assemble, admit of ready expansion or reduction in volume and capacity of the boiler through corresponding increase or decrease of the number of sections, and my new boilers possess the further advantage that, in making repairs, one or more sections may be readily replaced instead of necessitating the replacement of the entire boiler.

The present invention is not limited to the specific details set forth in the foregoing examples which should be construed as illustrative and not by way of limitation, and in view of the numerous modifications which may be effected therein without departing from the spirit and scope of this invention, it is desired that only such limitations be imposed as are indicated in the appended claims.

I claim as my invention:

1. In a house heating boiler, a plurality of interconnected section castings including a pair of end castings, said castings having inner hollow portions constituting the main water compartment and an auxiliary quick-heating water compartment and forming a fire pot and a heating gas compartment communicating with said fire pot, and said inner hollow portions in one of the end castings forming an opening in said end casting for receiving the wind pipe of a fluid fuel burner, partition means in an inner hollow portion of each casting extending across said hollow portion from the inner wall thereof to the outer wall thereof for separating the inner hollow space of each casting into a distinct upper hollow chamber and a distinct lower hollow chamber, said upper hollow chambers of the castings forming said main water compartment of the boiler and said lower hollow chambers of the castings forming said auxiliary quick-heating water compartment of the boiler, said fire pot having a thin coating of plastic refractory material, and means comprising conduits extending from the main water compartment to the auxiliary quick-heating water compartment for fluid circulation between said water compartments.

2. In a house heating boiler, a plurality of interconnected section castings including a pair of end castings and an intermediate casting, said castings having inner hollow portions constituting the main water compartment and an auxiliary quick-heating water compartment and forming a fire pot and a heating gas compartment communicating with said fire pot, and said inner hollow portions in one of the end castings forming an opening in said end casting for receiving the wind pipe of a fluid fuel burner, partition means in an inner hollow portion of each casting extending across said hollow portion from the inner wall thereof to the outer wall thereof for separating the inner hollow space of each casting into a distinct upper hollow chamber and a distinct lower hollow chamber, said upper hollow chambers of the castings forming said main water compartment of the boiler and said lower hollow chambers of the castings forming said auxiliary quick-heating water compartment of the boiler, said fire pot having a coating of plas-

tic refractory material of adequate thickness to absorb heat and to radiate heat back to the flame of the burner and sufficiently thin to transfer heat therethrough to the fluid in the water compartment, and means comprising conduits extending from the main water compartment to the auxiliary quick-heating water compartment for fluid circulation between said water compartments.

3. In a house heating boiler, a plurality of interconnected section castings including a pair of end castings and intermediate castings, said castings having inner hollow portions constituting the main water compartment and an auxiliary quick-heating water compartment and forming a fire pot and a heating gas compartment communicating with said fire pot, and said inner hollow portions in one of the end castings forming an opening in said end casting for receiving the wind pipe of a fluid fuel burner, partition means in an inner hollow portion of each casting extending across said hollow portion from the inner wall thereof to the outer wall thereof for separating the inner hollow space of each casting into a distinct upper hollow chamber and a distinct lower hollow chamber, said upper hollow chambers of the castings forming said main water compartment of the boiler and said lower hollow chambers of the castings forming said auxiliary quick-heating water compartment of the boiler, said fire pot having a thin coating of plastic refractory material, and means comprising conduits extending from the main water compartment to the auxiliary quick-heating water compartment for fluid circulation between said water compartments.

4. In a house heating boiler, a plurality of interconnected section castings including a pair of end castings, said castings having inner hollow portions constituting the main water compartment and an auxiliary quick-heating water compartment and forming a fire pot and a heating gas compartment communicating with said fire pot, partition means in an inner hollow portion of each casting for separating the main water compartment from the auxiliary quick-heating water compartment, said fire pot having a thin coating of plastic refractory material, and means comprising outside conduits extending from the main water compartment to the auxiliary quick-heating water compartment for fluid circulation between said water compartments.

5. In a house heating boiler, a plurality of interconnected section castings including a pair of end castings and an intermediate casting, said castings having inner hollow portions constituting the main water compartment and an auxiliary quick-heating water compartment and forming a fire pot and a heating gas compartment communicating with said fire pot, partition means in an inner hollow portion of each casting for separating the inner hollow space of each casting into a distinct upper hollow chamber forming part of said main water compartment and a distinct lower hollow chamber forming part of said auxiliary quick-heating water compartment, and means comprising outside conduits extending from the main water compartment to the auxiliary quick-heating water compartment for fluid circulation between said water compartments.

6. In a house heating boiler, a plurality of interconnected section castings including a pair of end castings and intermediate castings, said castings having inner hollow portions constituting the

main water compartment and an auxiliary quick-heating water compartment and forming a fire pot and a heating gas compartment communicating with said fire pot, partition means in an inner hollow portion of each casting for separating the main water compartment from the auxiliary quick-heating water compartment, said fire pot having a coating of plastic refractory material of adequate thickness to absorb heat and to radiate heat back to the flame of the burner and sufficiently thin to transfer heat therethrough to the fluid in the water compartment, and means comprising outside conduits extending from the main water compartment to the auxiliary quick-heating water compartment for fluid circulation between said water compartments.

7. The combination claimed in claim 1, and having the partition means between the water compartments obliquely inclined to the axis of the boiler.

8. The combination claimed in claim 5, and having the partition means between the water compartments obliquely inclined to the axis of the boiler.

9. In a house heating boiler, a fluid fuel burner, a plurality of interconnected section castings including a pair of end castings and an intermediate casting, said castings having inner hollow portions constituting the main water compartment and an auxiliary quick-heating water compartment and forming a fire pot and a heating gas compartment communicating with said fire pot, partition means in an inner hollow portion of each casting for separating the main water compartment from the auxiliary quick-heating water compartment, said auxiliary quick-heating water compartment forming a water lining for the fire pot and comprising a floor portion and a wall portion communicating with and extending upwardly from said floor portion, and means comprising conduits extending from the main water compartment to the auxiliary quick-heating water compartment for fluid circulation between said water compartments.

10. In a house heating boiler, a plurality of interconnected section castings including a pair of end castings and an intermediate casting, said castings having inner hollow portions constituting the main water compartment and an auxiliary quick-heating water compartment and forming a fire pot and a heating gas compartment communicating with said fire pot, and said inner hollow portions in one of the end castings forming an opening in said end casting for receiving the wind pipe of a fluid fuel burner, partition means in an inner hollow portion of each casting for separating the inner hollow space of each casting into a distinct upper hollow chamber and a distinct lower hollow chamber, said upper hollow chambers of the castings forming said main water compartment of the boiler and said lower hollow chambers of the castings forming said auxiliary quick-heating water compartment of the boiler, and means comprising outside conduits integral with one of said castings and extending from the main water compartment to the auxiliary quick-heating water compartment for fluid circulation between said water compartments.

11. In a house heating boiler, a plurality of interconnected section castings including a pair of end castings and an intermediate casting, said castings having inner hollow portions constituting the main water compartment and an auxiliary quick-heating water compartment and forming a fire pot and a heating gas compartment

communicating with said fire pot, partition means in an inner hollow portion of each casting for separating the main water compartment from the auxiliary quick-heating water compartment, and means comprising outside conduits integral with one of said castings and extending from the main water compartment to the auxiliary quick-heating water compartment for fluid circulation between said water compartments.

12. In a house heating boiler, a plurality of interconnected section castings including a pair of end castings and an intermediate casting, said castings having inner hollow portions constituting the main water compartment and an auxiliary quick-heating water compartment and forming a fire pot and a heating gas compartment communicating with said fire pot, partition means in an inner hollow portion of each casting for separating the main water compartment from the auxiliary quick-heating water compartment, and means comprising outside integral conduits on said castings and extending from the main water compartment to the auxiliary quick-heating water compartment for fluid circulation between said water compartments.

13. In a house heating boiler, a fluid fuel burner, a plurality of interconnected section castings including a pair of end castings and an intermediate casting, said castings having inner hollow portions constituting the main water compartment and an auxiliary quick-heating water compartment and forming a fire pot and a heating gas compartment communicating with said fire pot, partition means in an inner hollow portion of each casting for separating the main water compartment from the auxiliary quick-heating water compartment, said fire pot having a coating of plastic refractory material of adequate thickness to absorb heat and to radiate heat back to the flame of the burner and sufficiently thin to transfer heat therethrough to the fluid in the water compartment, said auxiliary quick-heating water compartment forming a water lining for the fire pot and comprising a floor portion and a wall portion communicating with and extending upwardly from said floor portion, and outside integral conduits on said castings and extending from the main water compartment to the auxiliary quick-heating water compartment for fluid circulation between said water compartments.

14. In a house heating boiler, a plurality of interconnected section castings including a pair of end castings, said castings having inner hollow portions constituting the main water compartment and an auxiliary quick-heating water compartment and forming a fire pot and a heating gas compartment communicating with said fire pot, and said inner hollow portions in one of the end castings forming an opening in said end casting for receiving the wind pipe of a fluid fuel burner, partition means in an inner hollow portion of each casting extending across said hollow portion from the inner wall thereof to the outer wall thereof for separating the main water compartment from the auxiliary quick-heating water compartment, another section casting connected to one of said end castings on the outside of said end casting, said other section casting having inner hollow portions communicating with and constituting an extension of the main water compartment and forming an extension of said heating gas compartment, and means comprising conduits extending from the main water compartment to the auxiliary quick-heating water compartment.

partment for fluid circulation between said water compartments.

15. In a house heating boiler, a plurality of interconnected section castings including a pair 5 of end castings, said castings having inner hollow portions constituting the main water compartment and an auxiliary quick-heating water compartment and forming a fire pot and a heating gas compartment communicating with said 10 fire pot, and said inner hollow portions in one of the end castings forming an opening in said end casting for receiving the wind pipe of a fluid fuel burner, partition means in an inner hollow portion of each casting for separating the main

water compartment from the auxiliary quick-heating water compartment, a plurality of other section castings connected to one of said end castings on the outside of said end casting, said other section castings having inner hollow portions communicating with and constituting an extension of the main water compartment and forming an extension of said heating gas compartment, and means comprising outside conduits extending from the main water compartment to 10 the auxiliary quick-heating water compartment for fluid circulation between said water compartments. 5

AARON KLOTZMAN.
